UNITED STATES PATENT OFFICE.

EDWARD B. ROTH, OF ST. LOUIS, MISSOURI, ASSIGNOR TO B. ROTH TOOL COMPANY, OF ST. LOUIS, MISSOURI, A CORPORATION OF MISSOURI.

EMBOSSING AND PRINTING PRESS.

No. 862,108.

Specification of Letters Patent.

Patented July 30, 1907.

Application filed March 17, 1905. Serial No. 250,526.

To all whom it may concern:

Be it known that I, EDWARD B. ROTH, a citizen of the United States, and a resident of the city of St. Louis and State of Missouri, have invented a new and useful 5 Improvement in Embossing and Printing Presses, of which the following is a specification.

My invention relates to printing presses and especially to embossing and printing presses and has for its principal objects to produce an automatic embossing 10 and printing press; to secure accuracy and certainty of operation; to increase the life of the dies; to uniformly ink the die; to avoid waste of ink; to economize wiping paper; to preserve the counter and avoid making a new counter each time a die is returned to the press; to provide 15 vide for adjusting the position of the die so as to avoid wiping it along the lines therein; to simplify the mechanism for reciprocating the counter plunger; to provide improved means to compensate for wear of the counter plunger or its bearing; and other objects hereinafter 20 more fully appearing.

My invention consists in the parts and in the arrangements and combinations of parts hereinafter described and claimed.

In the accompanying drawings forming a part of this 25 specification and wherein like symbols refer to like parts wherever they occur, Figure 1 is a front elevational view, partly in section, of my improved printing and embossing press; Fig. 2 is a side view of the press; Fig. 3 is a vertical sectional view through the press; 30 Figs. 4 and 5 are sectional views at right angles to each other through the bearing of the counter plunger and showing the counter plunger partly in elevation and partly in section, the counter and its chuck being shown attached and in section; Fig. 6 is a section on the 35 line 6-6 of Fig. 4; Fig. 7 is a view of the lower end of the plunger; Fig. 8 is a section on the line 8-8 of Fig. 4; Figs. 9 and 10 are top and bottom views, respectively, of the counter block with a counter therein; Figs. 11 to 40 15 are views of the track provided on both sides of the die chuck to guide the ink roller; Fig. 16 is a plan view of the die chuck and related parts; Fig. 17 is a section on the line 17-17 of Fig. 16; Fig. 18 is a section on the line 45 18-18 of Fig. 16; Fig. 19 is a section on the line 19-19 of Fig. 16; Fig. 20 is a broken plan view of the inking mechanism; Fig. 21 is a side view of the ink-roller-carrying arm and a sectional view through the 50 ink-receptacle; Figs. 22 and 23 are detail views showing the manner in which the ink roller is mounted in the arm; Fig. 24 is a fragmentary sectional view through the 55 ink-roller and ink-receptacle; Figs. 25 and 26 are detail views of the actuating crank arm for the ink-roller-carrying arms; Fig. 27 is a side view of the wiper; Fig. 28 is a plan view of the same; Fig. 29 is a vertical sectional view of the wiper; Fig. 30 is a view of a detail of the wiper;

Fig. 31 is a view of the winding drum for the wiping paper, and associated mechanism, the drum being shown in section; Fig. 32 is a view on the line 32-32 of Fig. 31; Fig. 33 is a perspective view of the winding drum with the spreader removed; Fig. 34 is a perspective view of the spreader.

The frame of the machine comprises and rests upon a base 1. From said base rise columns 2, 2 which are similar. Each comprises a bifurcated bottom portion having converging legs 3, 4 which are joined by a substantially horizontal part 5. From the bottom portion 65 rises a channeled portion 6, which is closed at the top by a plate 7 provided with a bearing 8. Intermediate their ends the columns are connected by a beam 9. A horizontal table 10, comprising parallel members 11, extends rearwardly from said beam and is supported 70 near its rear end by small columns or struts 12.

In the lower portions of the columns, bearings 13 are provided for a power shaft 14. Parallel with said power shaft, a main shaft 15 is journaled. A pinion 14^a on said power shaft meshes with a spur gear 15^a on said main shaft. The bearings 16 for said main shaft are made in two parts and the lower parts 17 are supported on screws 18. The latter are mounted in internally screw-threaded sockets 19 mounted on the base. The screws are provided with polygonal enlargements 20, by means of which they may be turned, and with set nuts 21 by means of which they may be fixed in position. The upper part of the bearings 16 is integral with the lower portion of the column. A brass bushing is mounted in the upper part of each bearing and a Babbitt-metal bushing in the lower part. Thus, the bearing can be adjusted to take up wear.

About the ends of the main shaft 15 an oil chamber is formed. Said chamber comprises side walls 23 and a divided rear wall 24 cast integral with the column. A 90 portion 25 of the rear wall and bottom wall of the chamber is integral with the lower part of each bearing 16. The outer wall 26 of the chamber is a removable plate.

From the main shaft 15 all the moving parts except the roller of the ink-well are driven. The moving parts comprise mechanism for vertically reciprocating a counter; mechanism for horizontally reciprocating a die; mechanism for inking the die and mechanism for wiping surplus ink from the die. These mechanisms will be described in order.

In the channeled portions of the columns 2, 2 extend pitman rods 27. These rods extend at their upper ends through bearings 8 in the plates 7 which cap the columns. At their lower ends the pitman rods carry cam straps 28, the latter being secured by nuts 29, 30. Bearing blocks 31 are provided on the lower sides of the cam straps where they are engaged by cams. At their sides the cam straps are equipped with bearing surfaces

which have sliding engagement with corresponding bearing surfaces on the side walls 23 of the oil chambers, which form, in effect, slideways to guide cam-straps. Toe-cams 32 are mounted on the ends of the main shaft 15 and coöperate with the cam-straps, bearing on the bearing blocks 31.

At their upper ends the pitman rods are connected to opposite ends of a cross-head 33. The ends of the cross-head have sliding bearings in the upper parts of the columns. Compression springs 34 surround the pitman rods 27 and bear at their upper ends against the ends of the cross-head. At their lower ends they rest upon adjustable tubular seats 35 which have screw-threaded engagement with blocks 36 integral with the columns. The springs tend to sustain the cross-head at the upper limit of its movement and hold the cam-straps always in engagement with the toe-cams. Thus, vibration, due to the motion of these parts, is almost wholly avoided.

26 A plunger 37 is secured to the cross-head 33. The plunger has a screw-threaded shank 38 which extends into the cross-head. A nut 39 is seated in a slot in the cross-head and adjustably secures the plunger to the cross-head. A nut 40 is arranged on the screw-threaded shank below the cross-head and serves as a lock-nut. Below the cross-head, the frame of the machine has a horizontal beam 41 mounted upon the columns 2, 2. The plunger 37 extends through a bearing 42 in said beam. This bearing is split on one side, the sides being drawn together by bolts. Thus, a means is provided for taking up wear of the plunger and the bearing. Rotation of the plunger in its bearing is prevented by a key 43. This key has an inclined face which rests upon an inclined seat in the plunger. The plunger bearing 35 is provided with a triangular way in which the key moves. A screw 44 passing through a slot in the key secures the latter in any position of adjustment. Said key serves the purpose of a key to prevent rotation of the plunger in its bearing and is capable of adjustment as it wears so as to insure an accurate fit. When an embossing press is engaged in doing fine work, no play of the plunger is permissible and, hence, the provision of means for taking up wear between the plunger and bearing and between the key and the bearing.

45 The lower end of the plunger is hollow in order to receive the shank of a counter-block 45. This counter-block is rectangular in plan and is provided with a round, centrally located shank 46 which is provided with a peripheral groove. The shank enters the recess in the end of the plunger and is secured by means of a tapered pin 47 mounted in holes in the plunger, and entering the peripheral groove of the shank 46 of the counter-block. The pin being tapered insures that the counter-block will be held firmly in place.

50 It is always desirable to wipe an embossing die at an angle to the direction of the lines therein, if possible. Hence, the die and counter are frequently set at an angle to the direction of movement of the table. For this purpose, provision is made for setting the counter-block in two positions. A vertical pin 48 is mounted in the face of the plunger. Two holes 49 are provided in the counter-block. When the latter is placed on the plunger the pin 48 may be placed in either hole. Obviously, any desired number of holes could be provided.

The counter-block, as its name implies, is intended to hold the counter. This is usually made of fine hard paste-board, faced with mill-board which is hammered up on the intaglio die and constitutes a relief die. Ordinarily, a new counter is hammered up each time a given die is put on the machine. In the present machine the counter can be saved. The counter-block has in its lower face a substantially rectangular recess, the opposite sides of which are undercut. In this recess, the counter 50, having beveled edges, fits. 70 Grooves with inclined bottoms are provided on one edge of the counter. Screws 51 in the counter-block enter said grooves and secure the counter in place. The screws engaging the inclined bottoms of the grooves will force the counter into close contact with 80 the bottom of the recess in the counter-block and will force the counter tightly against the opposite sides of the recess. Thus, it will be possible to remove the counter and replace it exactly as before. One end of the recess in the counter-block is closed by a plate 52 85 against which the counters always abut.

The embossing die is horizontally reciprocated. It is carried rearwardly to be inked and forwardly to be wiped and for the impression to be made in coöperation with the counter. The die is carried by a chuck 53 90 mounted on a table 54 which moves in ways in the parallel members 11 of the table 10 referred to above. The mechanism for reciprocating the table will be first described.

Upon the main shaft 15 and about midway between 95 its bearings an eccentric 55 is secured. Said eccentric has a discontinuous bearing surface comprising the substantially semi-cylindrical surface of the web 56 and the portion of the surface of a roller 57 lying in a continuation of the cylindrical surface of the web. 100 The web 56 connects two substantially circular disks 58 and the roller 57 is journaled in said disks. A split eccentric-strap 59 surrounds said eccentric and is confined laterally by said disks 58. The major portion of the bearing surface of the eccentric-strap is cylindrical. 105 At one point, however, there is a recess 60 the bottom wall of which forms a part of the bearing surface of the strap. The curvature of this wall is such that when the roller 57 is bearing thereon, the "throw" of the eccentric strap will cease, although at no time does the roller 110 cease to bear on the wall of the recess.

A lever 61, pivotally mounted on the base I, is connected with the eccentric strap by means of a skeleton pitman 62. The pitman is rigidly connected to the eccentric strap and is pivotally connected to the lever. 115 At its upper end the lever 61 is pivotally connected to a block 63 on the reciprocating table 54 by means of a link 64 which is pivotally connected to both. Said block 63 is provided with a tapering recess and a wooden block is seated in the bottom of the recess. A stop pin 120 65 is adjustably mounted in the beam 9 of the frame, with which it has screw-threaded engagement. A set nut 66 is provided to lock the pin in any position of adjustment. The stop pin corresponds in shape to the recess in the block 63. It is so located that it shall stop 125 the reciprocating table when the die thereon is immediately below the plunger. The recess in the eccentric strap is so positioned and proportioned that the roller 57 shall enter the recess just as the stop-pin engages the block and stops the table, and shall remain therein 130

while the counter descends and engages the die and retreats. When the roller passes out of the recess the reciprocating table is caused to begin its rearward movement.

- 5 The chuck 53 comprises a base having a substantially cylindrical flange 67. Two clamping pieces 68, having rabbeted inner edges are secured in said base at diametrically opposite points by screws 69. Between said clamping pieces the base has a raised portion which 10 has a central groove parallel therewith. In said groove a right-and-left-hand screw 70 is secured. Clamping plates 71 fit over the said raised portion of the base and have their ends rabbeted to fit the rabbeted edges of the clamping pieces 68. These clamping plates have 15 screw-threaded engagement with said right-and left-hand screw 70 whereby they may be caused to approach or recede from each other. The embossing die is clamped between said clamping plates 71 which are in turn clamped down by the clamping pieces 68.
- 20 Like the counter-block, the chuck 53 can be rotated through a small angle so as to set the die in such direction that the direction of movement of the wiping paper shall be across the lines. The chuck is secured to the table by screws 72. Two holes 73 are provided 25 in the reciprocating table, in either of which the screws may be inserted.
- The inking mechanism is arranged on the table 10 at the rear thereof so as to ink the die during the rearward portion of its travel. Standards 74 rise at each side of 30 the table from the members 11. At their upper ends said standards have bearings in which rock shaft 75 is journaled. A slotted crank arm 76 is secured on one end of said rock-shaft by a set screw 77. An adjusting screw 78 extends longitudinally of the slot in said crank arm 35 and is secured against longitudinal movement therein by means of a collar 79 and a head 80. A squared block 81 is slidably mounted in the slot in said arm and has screw-threaded engagement with said adjusting screw whereby it may be adjusted to any position in said slot.
- 40 On one side the block 81 carries a crank pin 82. On the other side, the block is provided with a screw on which a set nut 83 is mounted. The actuating rod 84 for the ink roller is pivotally connected to said crank pin 82. At its lower end said rod is provided with a 45 roller which engages a cam 85 on the main shaft 15. The rod is supported at its lower end by a link 86 which is pivotally connected to the frame of the machine. By adjusting the block 81 on the crank arm 76, the point of connection of the actuating rod 84 is adjusted and thus 50 the angle through which the rock-shaft is turned may be varied.

A frame 87 is secured to the rock-shaft 75 and is provided with parallel arms. At the ends of the arms angular members 88 are pivotally mounted. Said angular 55 members have upper portions extending substantially parallel with the arms. A pin 89 secured in the arm passes through the angular member. A spring 90, surrounding said pin and bearing at one end upon the nut 91 on the end of said pin and at the other end on said 60 angular member, tends to hold said upper portion of said angular member and said arm in contact. A screw 92 is adjustably mounted in said angular member to determine the minimum distance between said upper portion of said angular member and said arm. The 65 other end of said angular member is divided into two

parts; one part 93 is fixed and the other part 94 is pivoted. The exterior surface of the split portion is tapering. A ring 95 is mounted on such tapering surface to hold the parts together when it is desired to do so. A spherical bearing 96 is formed in the two parts 93, 94, 70 and in such bearing a zonal segment of a sphere or a ball 97 is mounted. This ball is pierced by a cylindrical hole which forms a bearing for the reduced end of the ink-roller-shaft 98.

At the rear end of the table 10 an ink-pan receiver 99 75 is permanently mounted. Its sides provide bearings for the shaft of the feed-roller. In this receiver the ink-pans or ink-receptacles are set. These pans may have one, two or more compartments, depending on the colors in which different portions of the impression are to 80 be printed. In the case chosen for illustration the ink-pan 100 has three compartments separated by partitions. The partitions are slotted in a manner corresponding to the bearings in the ink-pan frame 99. A feed-roller 101 is used having as many cylindrical sections as there are compartments in the ink pan mounted on a shaft 102. This is journaled in the ink-pan receiver and the sections depend into the ink-pan. Between the sections shields 103 are mounted on the shaft. These shields are re-bent sheet metal plates which 90 straddle the partitions of the ink pan and serve to prevent the ink in one compartment being carried into the next compartment through the slot in which the shaft 102 rests. On the end of the feed-roller-shaft a sprocket 102^a is mounted. This is connected with a sprocket 104 95 on the power shaft by a sprocket chain 105. Thus, so long as the machine is running the feed-roller will be rotated.

To prevent too much ink being carried up by the feed-roller scrapers are provided. A bar 106 is secured 100 to the ink-pan frame. To this bar as many scrapers 107 are secured by screws 108 as there are compartments in the ink-pan. Each scraper has a flange 109 on its rear edge in which two screws 110 are secured. The screws 110 enter holes in the bar 106. By means of the screws 105 110 the scrapers can be adjusted both transversely and angularly and thus their edges can be adjusted exactly parallel with the sections of the roller. It is desirable to have the scrapers thus independently adjustable because the different colored inks have different consistencies. Hence the scrapers may be set at different distances from the different sections of the ink-roller. When only one color is being used, of course, it is unnecessary to use a pan with more than one compartment.

Curved tracks 111 extend forwardly from the ink-pan 115 frame to guide the ink-roller. On either side of the die chuck 53 adjustable tracks are arranged. The latter comprises a base plate 112 having a horizontal flange through which screws pass to secure it to the reciprocating table 54. The upper edge of the base plate is 120 inclined and near said edge are arranged two aligned slots 113 parallel therewith. A track plate 114 is secured to the base plate by means of screws passing through said slots. The track plate has an inclined shoulder 115 having the same inclination as the inclined edge of the base plate and which rests upon said inclined edge. Thus, the tread of the track plate will be parallel with the surface of the reciprocating table 54.

The ink-roller shaft 98 carries an ink-roller 116 and near its ends guide rollers 117. The guide rollers run 130

on the curved tracks 111 and the track plates 114 and thus hold the ink-roller in the position desired. By adjustment of the track plates 114 the pressure of the ink-roller upon the dies can be regulated and variations in the thickness of the dies may be provided for. The curved tracks 111 serve to guide the ink-roller so that it will properly engage the feed-roller and will run onto the track plates smoothly. The springs 90 hold the ink-roller yieldingly in contact with all the parts the latter engages. The angular members 88 being independently mounted and the ink-roller shaft being mounted in a ball-and-socket bearing, the ink roller can adjust itself within limits, to any surface with which it engages. This is a matter of much importance as it insures the proper inking of the die although the latter may have been slightly tilted in some way.

An arm 118 is secured to the rock-shaft 75. A rod 119, provided with a handle 120, and a catch 121, is pivotally connected to said arm. By means of this rod the ink-roller and its actuating rod 84 may be raised so that they cannot be actuated by the actuating cam 85, the catch 121 engaging the bottom of the notch in the beam 41 through which the rod extends. The ink-roller is thrown into this position when the counter is being hammered up.

After the die has been inked, and as it is moving forward to its position under the plunger, it is wiped to remove the ink from its surface. This is automatically accomplished by the following mechanism: 30 Bracket arms 122 extend rearwardly from the beam 41. Other bracket arms 123 extend rearwardly from the upper ends of the columns 2, 2. The latter arms support a shaft 124 upon which the roll of wiping paper 125 is mounted. Upon the bracket arms 122, a winding drum 126 is rotatably mounted. The wiping paper passes downwardly from the roll, over the lower face of a wiping pad and up to the drum 126. The wiping pad is reciprocatingly mounted in hangers 127 depending from the bracket arms 122, and fixed at 40 their lower ends to the table 10. The wiping pad comprises a plate 128 having a dove-tail groove across its upper face. A T-shaped guide member 129 fits in said dove-tail groove, the central flange of such member extending vertically and terminating in guides 130. 45 The guides enter slots 131 in the hangers 127. A pin 133 is secured to the outer face of each guide and to this pin a tube 134 is connected by means of an eye at its lower end. An eye 135 is fixed in the hanger above the slot therein and through it extends a rod 136 which 50 enters the tube 134. The lower end of the tube is transversely slotted to accommodate a pin 137 secured in the rod 136 and extending beyond the sides of the tube. The rod 136 is secured in place by a nut 138. The upper end of the tube 134 is screw-threaded and 55 carries a collar 139. Between said collar 139 and said pin 137 a compression spring is arranged bearing at its opposite ends in said parts. This spring tends to hold the wiping pad in its uppermost position. Its tension may be adjusted by means of the nut 138 or the collar 60 139. To engage and wipe the die the wiping pad is pressed downwardly by mechanism about to be described.

A rock-shaft 140 is journaled in the hangers 127 above the plate 128. On this rock-shaft rearwardly 65 extending arms 141 are mounted. The central verti-

cal flange of the guide member 129 is slotted near its opposite ends to receive such arm 141. Each of these slots is covered by a slotted plate 142 of hardened steel which is secured by means of screws passing through slots therein. A flange 143 is provided at the upper 70 end of the plate and an adjusting screw 144 therein bears on the top of the guide member. The arms 141 enter the slots of these plates 142 and bear therein. At one end of the rock-shaft 140 a forwardly extending arm 145 is secured. To this is pivotally connected 75 an actuating rod 146 which bears at its lower end upon a cam 147 on the main shaft 15. Intermediate its ends the actuating rod is provided with a turnbuckle 148 whereby its length may be adjusted.

At opposite sides of the wiping pad brackets 149 are 80 secured to the central vertical flange of the guide member 129. The brackets extend laterally and downwardly and carry in the lower ends guide rollers 150 for the wiping paper. On one side of the plate 128 a clamping bar 151 is secured by screws. On the opposite side of the plate a roller 152 is journaled. A ratchet wheel 153 is secured to one end of the roller. A pawl 154 is secured in position to engage the ratchet wheel and is held in contact therewith by a spring 155. A squared projection 156 extends beyond the ratchet 90 wheel and provides means for rotating the roller. An apron 157 is secured at one end to the roller 152 and its other end is clamped by the clamping bar 151, the apron passing from the roller to the bar beneath the plate 128. A pad 158 of rubber or like resilient material is placed above the apron and in contact therewith. Between the rubber pad and the plate 128 are facing strips 159. Of these, preferably, four of different widths are provided. The facing strips are arranged transversely to the direction of reciprocation, 95 so that the roller travels in the direction of their width or narrower dimension. When a wide die is being used all four facing strips are used, as indicated in Fig. 27. When, however, narrower dies are to be used, less wiping area is required. Then one or more of the 100 facing strips can be removed and the effective area of the face of the pad may be reduced. In Fig. 29 two facing strips are shown in use and a single one may be used alone. The rate of the feed of the wiping paper is varied to correspond to the effective area of the wiping pad. Thus a considerable saving in wiping paper may be accomplished.

The winding drum 126 is made in sections. On a shaft 160, journaled in the brackets 122, is fixed a disk 161, the edge of which is serrated with ratchet teeth. 115 The sections of the drum are each slightly smaller than quadrants of a cylinder and are secured to said disk or ratchet 161 by bolts 162. At the opposite end of the drum a disk 163 is slidingly mounted on the shaft 160. It is provided with a centrally located projection 164 120 which is cylindrical for a portion of its length and terminates in a frusto-conical section. The winding-drum is provided with a peripheral groove near the end adjacent to said loosely mounted disk. In said groove there is an endless coiled spring 165 which tends to draw the ends of the drum sections together. The projection 164 on the loose disk 163 serves to spread the sections apart so that when the parts are assembled the drum is cylindrical. The paper which is wound on the drum is smeared with ink and, consequently, 130

the layers adhere to each other. To remove the roll, the loose disk 163 is moved on the shaft so as to withdraw the projection 164. Then the spring 165 draws the ends of the drum sections together, as indicated 5 in Fig. 33. This so reduces the diameter of the drum that the roll of paper can be readily slipped.

The bearing for the end of the shaft 160 nearest the loose disk is open at the top to permit the removal of the shaft. The opposite end of the shaft 160 terminates in a ball 166 and is journaled in the hollow end of 10 a shaft 167 which carries a portion of the actuating mechanism. The end of the bracket 122 at this side of the feed roller is made U-shaped to provide two bearings 168 and 169. In these bearings the shaft 167 is 15 journaled. The end of the shaft toward the winding drum is hollow and is provided with clutch-teeth 170. The ratchet wheel 161 on the shaft 167 is provided with a tubular extension having corresponding clutch-teeth 171. A peripheral groove 172 for a shift-lever 173 is 20 also provided in said tubular extension. Thus, the rotation of the drum may be stopped at any time without stopping the actuating mechanism.

Between its bearings the shaft 167 carries a gear wheel 174 and a ratchet wheel 175. The ratchet wheel 25 175 is fixed on the shaft while the gear wheel 174 is loosely mounted thereon. A disk 176 is rigidly connected to the gear wheel 174 and lies between it and the ratchet wheel 175. Upon this disk two pawls 177 are mounted and are held in contact with the 30 ratchet wheel 175 by springs 178. Thus, there is a tendency to rotate the shaft 167 and the winding drum 126 in one direction only. To prevent any possible rotation of the drum in the opposite direction a pawl 179 is pivoted on one of the bracket arms 122 in position to engage the ratchet wheel 161.

A loop 180 embraces the shaft 167 at one side of the gear wheel 174. The sides of said loop are L-shaped in cross-section; or may be said to have an internal flange which closely embraces the shaft but not tightly. 40 The loop is provided with gear-teeth on one side forming a rack 181 which meshes with the gear wheel 174. Said loop is integral with one part of an actuating rod 182. The parts of said rod are connected by a turn-buckle 183 by means of which the length of the actuating rod may be varied. At its lower end the actuating rod is provided with a roller which bears upon a cam 184 on the main shaft 15. A link connects the rod with the frame and holds it in proximity to the cam. The rate of feed of the wiping paper is regulated by 50 adjusting the length of said rod. At the lower limit of its movement the loop 180 settles down upon the shaft 167. If the length of the actuating rod is now adjusted so that its lower end will bear upon that part of the cam 184 having the shortest radius from the center of rotation, the actuating rod will bear upon the cam throughout its complete rotation. Hence, the actuating rod will be given its maximum stroke and the wiping paper will be fed at its maximum rate. To cause a 55 slower rate of feed it is only necessary to shorten the actuating rod. This will cause it to remain out of contact with the cam 184 during a portion of each revolution and thus the stroke of the actuating rod will be shorter. By such adjustments, the rate of feed of the wiping paper can be varied so as to feed up only the 60 length of paper soiled on the face of the wiping pad,

whether the effective wiping surface of the pad be its maximum or minimum.

The operation of the machine will now be described.

Consider the parts in the positions shown in Figs. 1, 2 and 3. The table 54 is now at the rearmost point in 70 its movement, and the plunger 37 is at the uppermost limit of its movement. Upon further rotation of the main shaft the table 54 will be moved forwardly; the ink-roller will move rearwardly over the die toward the feed roller in the ink-receptacle; and the wiping pad 75 will be lowered into position to engage the die as the latter passes beneath it. The table and die will reach their foremost positions before the main shaft has completed half a revolution, and will be stopped by the stop-pin 65. The plunger now descends and an impression is made between the counter and die, the plunger rising before the table and die begin their rearward movement. The table and die are then moved rearwardly; the wiping pad is raised and the wiping paper is fed by a partial rotation of the drum 80 85 126; as the table and die approach their rearmost positions the ink-roller moves toward them and finally over the die; and finally, after a complete rotation of the main shaft the parts assume the first position.

Obviously, my machine is capable of modification 90 within the scope of my invention and, therefore, I do not wish to be limited to the specific construction shown and described.

What I claim as my invention and desire to secure by Letters Patent is:

1. A press comprising a frame, a cross-head reciprocatingly mounted in said frame, an actuating shaft, cams on said shaft, rods connected to said cross-head and provided with cam straps, springs surrounding said rods and bearing at one end on said cross-head, and adjustable supports 100 for the opposite ends of said springs.

2. A press comprising a frame, a cross-head reciprocatingly mounted in said frame, an actuating shaft, cams on said shaft, rods connected to said cross-head and provided with cam-straps to engage said cams, respectively, bearings on said frame slidably engaged by said rods, respectively, and slideways on said frame engaged by said cam-straps, respectively and springs holding said cam-straps in engagement with said cams, respectively.

3. A press comprising a frame, an actuating shaft 110 mounted in said frame, oil-chambers surrounding the ends of said shaft and having walls formed to constitute a slideway, cams mounted on shaft and arranged in said oil-chambers, respectively, cam-engaging members having sliding engagement with said slideways, respectively, and a cross-head operatively connected with said cam-engaging members.

4. The combination in an embossing and printing press of a die and means for wiping the same and means for winding the wiping material, said winding means comprising a shaft, a disk mounted on said shaft, cylindrical segments loosely connected at one end to said disk, means tending to draw the free ends of said segments together and means to spread said segments apart.

5. The combination in an embossing and printing press 125 of a die, means for winding the wiping material, said winding means comprising a shaft, a disk mounted on said shaft, cylindrical segments loosely connected at one end to said disk, means to draw the free ends of said segments together, and a disk mounted on said shaft and provided with a projection to spread the free ends of said segments apart, said projection and said segments having relative movement longitudinally of the segments.

6. A press comprising a frame, an actuating shaft mounted in said frame, a collapsible winding drum mounted on said frame, a ratchet disk secured to said drum, a pawl to prevent rotation of said drum in one direction, a ratchet wheel connected with said drum, a disk provided

- with pawls in position to engage said ratchet wheel, and adjustable means to transmit motion from said actuating shaft to said disk.
7. A press comprising a frame, an actuating shaft mounted in said frame, a stub-shaft journaled in bearings in said frame, one end of said shaft being tubular, an open bearing on said frame, a drum shaft journaled in said open bearing and in the tubular end of said stub-shaft, a drum on said drum-shaft, clutch members on said stub-shaft and said drum-shaft, a ratchet wheel secured to said stub-shaft, a gear wheel loosely mounted on said stub-shaft and provided with pawls to engage said ratchet, and means to transmit motion to said gear wheel from said actuating shaft.
15. 8. A press comprising a frame, a plunger reciprocatingly mounted in said frame, a bearing in said frame for said plunger provided with an angular key-seat, and a key adjustable laterally with respect to said plunger.
9. A press comprising a frame, a plunger reciprocatingly mounted in said frame, a bearing in said frame for said plunger, said bearing and said plunger being provided with key seats and one of said seats having an inclined bottom, and a key fitting in said key seats and longitudinally adjustable therein.
25. 10. A press comprising a frame, a plunger reciprocatingly mounted in said frame and provided with a key-seat having an inclined bottom, a key having an inclined face adjustably secured in said key-seat, a bearing in said frame for said plunger and having a bilateral key-seat to receive 30 said key.
11. A press comprising a reciprocatingly mounted plunger, a counter-block, means to secure said counter-block to said plunger, and means to fix said counter-block in a plurality of positions at an angle to each other, said means comprising a plurality of holes and a pin engaging therewith.
12. A press comprising a reciprocatingly mounted plunger provided with a tubular end, a counter-block, a shank on said counter-block fitting in said tubular end of said 40 plunger and provided with a peripheral groove, a pin in said plunger and entering said peripheral groove, and means to fix said counter-block in a plurality of positions at an angle to each other.
13. An embossing and printing press comprising a frame, a carrier thereon, a die in said carrier, a plunger reciprocatingly mounted in said frame opposite said die, a counterblock rotatably secured to said plunger and provided with a recess, a counter fitting in said recess, and means to fix said counter in place, said counter being 45 opposite said die and arranged to co-operate therewith.
14. A press comprising a reciprocatingly mounted plunger, a counter-block secured to said plunger and provided with a dovetail groove to receive a counter, a counter fitting in said groove, notches in said counter having in-
- clined bottom walls and set screws in said counter-block 55 and engaging said inclined bottom walls of said notches, whereby said counter will be held in close contact with the bottom of said dovetail groove in said counter.
15. A press comprising a reciprocating die, mechanism to ink said die, and mechanism to wipe said die, said 60 wiping mechanism comprising means for varying the effective area of the wiping face, said means comprising a flexible pad and interchangeable pieces for distending the same.
16. A press comprising a reciprocating die, inking mechanism to ink said die, a wiping pad provided with means whereby its effective wiping face may be varied, said means comprising a flexible pad and interchangeable pieces for distending the same and adjustable mechanism for feeding paper across the wiping face of said wiping pad. 70
17. A press comprising a reciprocatingly mounted die, mechanism to ink said die, and mechanism to wipe said die, said die wiping mechanism comprising a plate, an apron passing over the face of said plate, and a strip between said plate and said apron, the dimension of said 75 strip measured in the direction of movement of the inking mechanism being less than the corresponding dimension of said plate, whereby the effective wiping area is reduced.
18. A press comprising a reciprocatingly mounted die, mechanism to ink said die, and mechanism to wipe said die comprising a plate, wiping paper passing over the face of said plate, means to feed said wiping paper, and a strip between said paper and said plate, the dimension of said strip measured in the direction of movement of the inking mechanism being less than the corresponding dimension of 85 said plate, whereby the effective wiping area is reduced.
19. A press comprising a reciprocatingly mounted die, mechanism to ink said die, and mechanism to wipe said die comprising a plate, a resilient pad thereon, an apron passing over said pad, and a plurality of removable facing 90 strips between said pad and said plate.
20. A press comprising a frame, slotted members secured to said frame, a wiping pad reciprocatingly mounted on said frame and having guides extending into said slotted members, telescoping members arranged adjacent 95 each of said guides and each of which is provided with a spring seat, and a spring mounted between said spring seats, one of said telescoping members being connected to one of said slotted members and the other being connected to one of said guides. 100
- In testimony whereof I have signed my name to this specification in the presence of two subscribing witnesses this 13th day of March, 1905, at St. Louis, Missouri.
